(57) **CLAIM**

The ornamental design for a PPR bra, as shown and described.

DESCRIPTION

FIG. 1 is a perspective view of a PPR bra showing our new invention;

FIG. 2 is a perspective view of a PPR bra, shown in a second embodiment;

FIG. 3 is a perspective view of a PPR bra, shown in a third embodiment; and,

FIG. 4 is a perspective view of a PPR bra, shown in a fourth embodiment.

The other side of FIGS. 1-4 being a mirror image.

1 Claim, 4 Drawing Sheets
